UNITED STATES PATENT OFFICE.

LLOYD G. COPEMAN, OF FLINT, MICHIGAN, ASSIGNOR TO EDWIN W. ATWOOD, OF FLINT, MICHIGAN.

REFRIGERATING APPARATUS.

Application filed July 27, 1921. Serial No. 487,897.

To all whom it may concern:

Be it known that I, LLOYD G. COPEMAN, a citizen of the United States, residing at Flint, in the county of Genesee and State 5 of Michigan, have invented certain new and useful Improvements in Refrigerating Apparatus, of which the following is a specification.

This invention relates to refrigeration, 10 and has for its object refrigerating apparatus arranged to use ordinary service water such as is drawn from the taps for domestic use. Coupled with this service water refrigeration is a controllable waste which 15 is arranged to bring the water in almost immediate contact with the food chamber for the purpose of securing the maximum refrigerating effects during very hot weather.

In the drawings,—

20 Fig. 1 is an elevation of the apparatus, some of the parts being shown in section.

Fig. 2 is a vertical cross section of a box equipped with my refrigerating apparatus.

Fig. 3 is a horizontal cross section on the 25 line 3—3 of Fig. 2 of a box equipped with my refrigerating apparatus.

The box is made in any conventional way of wood or other material and is suitably insulated to hold the low temperature conditions desired for a food chamber. This 30 box is divided into right and left food chambers which are connected at top and bottom by passage-ways *a* and *b*. Within the walls of the food chambers are a plurality of coils *c*. These include the top, bottom and side walls. These coils are embedded in a hardened plastic composition which forms a stone-work *e* completely enclosing the coils.

40 Now referring to Fig. 1, it will be seen that the water enters the refrigerator through the main *d*, which is connected with the pressure-controlled switch operator *f* and the pump *g* operated by the motor *M*, 45 which in turn is controlled by the switch *h* that is operated by the pressure-controlled switch operator *f*. When the pressure in the storage tank *i* falls below a given point, the member *f* closes the electric switch *h* and 50 causes the motor to again operate the pump to pump more water through the main *d*, the coils *c* and into the auxiliary storage tank *j*, from which it passes through the check valve *k* into the main storage tank *i*.

These storage tanks, of course, have a head 55 of air in them which permits a certain range of pressures within the tank.

Now referring to Fig. 2, it will be seen that the header *m* is located in the bottom of the box. From this lower header rises a 60 pipe *n* provided with a valve *o* by which the outlet from said pipe may be controlled. This pipe turns and runs along the top partition and is provided with a pair of branches *p* which act as spray pipes. 65

It will be found that the stone-work *e* of the box is encased by a sheet metal sheathing *q* which is only slightly spaced from the stone-work *e*. Water from the spray pipe *p* spreads over the top of this sheathing *q* 70 and runs down between the sheathing and the stone-work in a film and wastes out through the waste pipe *r*.

The operation is as follows: When any 75 service water is drawn from the storage tank *i*, as for instance, from the tap *s*, it of course depletes the quantity of water in the auxiliary tank *j*. When the water has fallen below a given quantity obviously the pressure in the auxiliary tank falls and 80 starts the pump working again. This sends water through the refrigerating coils in the box and of course serves to lower the temperature of the refrigerator. In moderate weather this will be sufficient to keep the refrigerator cool providing the water is drawn from a good cold well. Most wells average from 49 to 55 degrees and such a 85 refrigerating medium will do for moderate temperatures. However, when extreme summer temperature has come it will be found that water will have to be wasted in order to keep the temperature down to the desired 90 level. In fact, mere wasting of the water drawn through the coils will not be sufficient 95 in extreme summer weather. There must be a more immediate exposure of the water to the atmosphere contained within the box. This is accomplished by a film of water that is distributed down the sides of the box by 100 virtue of the sheathing *q* and the spray pipes *p* on top of the sheathing.

By providing the valve *o* in the pipe *n* the amount of spray delivered from the spray pipes may be regulated to accord with the 105 temperature of the atmosphere. This will waste enough water so that periodically the pressure in the auxiliary tank will fall be-

low a given point and the pump will again come into play. The auxiliary storage tank is highly insulated and also the connections with the auxiliary storage tank so that the 5 water that is contained therein will not lose its low temperature. Water that has once passed into the main storage tank will not return because of the check valve. Hence only water from the auxiliary insulated 10 tank is drawn upon for the waste. This is kept relatively cold by the insulation. The auxiliary tank being of small capacity the pressure therein is soon lowered and a 15 fresh quantity of cold water drawn through the coils.

What I claim is:

1. In refrigerating apparatus, the combination of a box, water circulating coils therein, a service connection with said coils 20 for drawing water therethrough for service purposes, a sheathing in said box forming a narrow space between the walls of the box and the sheathing for containing a film of water, a pipe leading from said coils for 25 drawing water taken from said coils and de-

livering the same on top of said sheathing to form a film of waste water.

2. In refrigerating apparatus, the combination of a box, a sheathing therein spaced from the walls of the box to form a water 30 film space, a plurality of coils in the walls of said box for circulating water therethrough, a service connection with said coils for drawing water through the coils for service use, and a pipe provided with a valve 35 for delivering water from the coils over the top of the sheathing to provide a film of water of controllable quantity.

3. In a refrigerating apparatus, the combination of a box, a sheathing therein spaced 40 from the walls of the box to form a water film space, a plurality of coils in the walls of said box for circulating water therethrough, and means for delivering a portion of such water from the coils over the top of 45 the sheathing and flowing the same in the form of a film down the walls of said sheathing.

In testimony whereof I affix my signature.
LLOYD G. COPEMAN.
